UNITED STATES PATENT OFFICE

GEORGE E. GROVER, OF NEW YORK, N. Y., ASSIGNOR TO FREDERICK T. TOWNE, OF PORT CHESTER, NEW YORK, AND JAMES S. HEDGES AND W. H. L. EDWARDS, OF NEW YORK, N. Y.

MULTIPLE-COIN-CONTROLLED TURNSTILE

Application filed July 24, 1928. Serial No. 294,954.

This invention relates to coin-controlled turnstiles for use in regulating the passage of persons at the entry or exit of cars, stations, buildings, parks, etc.

Such devices are ordinarily cumbersome, occupying valuable space, particularly when the prepayment coins are entered at points remote from the axis of the turnstile as is usual, and in which case dependence is placed upon electrical contrivances to release the stile restraining mechanism.

Obviously such stiles are expensive to install, not readily removable, frequently fail to function, causing annoyance and loss of time, and require expert mechanical and electrical attention, and are therefore costly to maintain and operate; furthermore, all such mechanisms are devised for operation upon the entry of a single coin and consequently are unavailable where two or more coins of different value are required as the passage price.

It is therefore an object of the present invention to provide a light weight, easily portable prepayment turnstile directly receptive of two coins at a point essentially at the axis of its rotatable arms, convenient of access.

A further feature is in the provision of a purely mechanical apparatus, selectively receptive of suitable coins and utilizing the same to secure release of the restraining mechanism whereby the stile arms may be given a fractional forward turn, thereafter becoming locked until further prepayment coins are inserted, the operation being entirely automatic.

Another purpose is to produce a turnstile that is instantly responsive to the entry of the coins, no appreciable delay being encountered, and which returns coins entered in excess of the necessary number, also all improper, thin coins or substitutes, and registers each full operation.

Other advantageous features are in the provision of yielding elements which serve to cushion the impact of a person against the stile arms, preventing bodily injury and also damage to the mechanism; in the design of an operative mechanism adapted for long wear under the severe service to which such mecha-

nisms are subjected, and which can be removed, as an entity, should occasion demand, and another substituted.

As will be seen this device may be easily repaired or assembled, and if it is desired it can be made reversible for the exit of passengers without the payment of any coins.

These and other important objects, which will become apparent as the description progresses, are attained by the novel design, construction and combination of parts as herein-after described and illustrated in the accompanying drawings, the same constituting a material part of this disclosure, and in which:

Figure 1 is a perspective view showing an embodiment of the invention as completely assembled in position for operation.

Figure 2 is a plan view of the structure with the housing, cover plate, and coin entrance escutcheon removed.

Figure 3 is a central longitudinal sectional view showing the main operative elements, looking from front to rear, on line 3—3 of Figure 2.

Figure 4 is a similar sectional view, taken in a plane at a right angle to Figure 3, on line 4—4 of Figure 2.

Figure 5 is a transverse sectional view taken approximately on line 5—5 of Figure 4.

Figure 6 is a perspective view, partially in section, of the coin determining and release mechanism.

The turnstile, as shown in Figure 1, comprises a hollow rectangular upright column 15 having an outwardly flanged bottom and being provided with a door 16 in one of its sides, the top of the column being flat and containing a central opening.

A cylindrical base 17 is bolted on the column by corner lugs 18, the base having an inreaching annular flange 19, (see Figures 3 and 4) in the outer portion of which is a seat for the lower race element of an antifriction bearing 20.

The upper race of the bearing is secured in a similar seat in the underside of a flange 21 formed on the lower end of a swivel cylinder 22 surrounded by a band 23, rigidly secured to it and having four pairs of radial

arm brackets 24, between which are bolted the gate arms 25.

Above the cylinder 22 is a short base ring 26, shaped to receive a cylindrical housing 27, having its upper end portion 28 extended straight across on one side, preferably the rear, tangent to the diameter and joined at right angles by walls 29 reaching from the center of the ring to the ends of the element 10 28, as best seen in Figure 1.

A D-shaped channel 30 extends interjacent the raised front and side walls, at the top of the housing, the inner wall 31 of the channel being spaced uniformly with the 15 outer wall and is of equal height therewith.

A semi-circular cover plate 32 is secured to the wall 31, as is also a rectangular cover coin escutcheon plate 33, and rear plate 34, these plates together completely covering 20 the opening in the top of the housing 27.

The present disclosure is that of a mechanism controlled by two coins of unlike denominations, to wit: a copper cent and a nickel five cent piece, the former being entered through the escutcheon slot 35, and the latter through the longer slot 36, offset slightly to the rear.

Each coin enters through its respective slot, passing magnets 37, (see Figures 3 and 30 4) to be engaged by spring actuated coin shooters 38-39, which project the coins downwardly and angularly towards the center to enter apertures 40-41, in the convergent angular upper ends of a double coin 35 chute 42, having a central partition 43 and containing angularly disposed runways 44-45, crossing each other at their upper ends.

Below the outer edges of the runways the copper coin, now at the right side of the 40 center of the chute, at the front, passes over the beveled face of a transverse guide 46 and the nickel coin correspondingly strikes the oppositely beveled face of a guide 47, whereby both coins are moved into the same 45 vertical plane and drop upon the upper exposed edge of a baffle 50-50' upon which the coins temporarily rest, this baffle being later on more fully described.

In the event that spurious coins have been 50 deposited, or that proper coins fail to enter the runways, such coins will be received in the casing 42' and follow the outer passages 51-52, which are connected at their lower ends, the connection being open at the bottom 53 permitting the coins to drop into a conduit 54 leading to a return coin cup 55, accessible through the side of the base 17 at the front, as best seen in Figures 1 and 4.

The conduit 54 extends down through an 60 opening in a frame 56 fixed in a circular recess in the top of the flange 19, of the base 17.

The frame 56 has four raised lugs, 57-57' at the front, and 58-58' at the rear, the latter pair having secured to them the rear 65 cuffed edge of the return coin chute 54, a

base plate 60 being held by screws to the tops of the four lugs.

Also formed on the upper side of the frame 56 between the lugs 57-57' is a raised block 61, and at the side between the lugs 57'-58' is another block 62, opposite to which is a lug 63.

Mounted on a circular seat, formed in the swivel ring 22, is a plunger ring 64 having four internal cam recesses 65.

Seated on the rim of the ring 64 is a locking ring 66 having four inner cam faces 67, terminating in distinct stops 68 at the ends of recesses 69.

Above the ring 64 is a ratchet ring 70 having an internal row of teeth 71, amongst which are four equally disposed spaces or teeth omissions 72, and fixed in the rim of the ring 70 are four inreaching angular hardened cam plates 73 disposed approximately 85 midway of the spaces 72, to engage a slide plate cam as will later be seen.

The several rings 64-66-70, which will later be more fully described, are fixed in the interior of the swivel ring 22, and extend 90 upwardly to a plane level with its upper edge, coincident with the band 23, and immediately below the housing base ring 26, which is fixed on the lugs 57-57', and 58-58' of the frame 56.

The turnstile is brought into its finally adjusted position by a plunger 75 slidable at one end in the lug 63 and having at the other end a head 77 containing a longitudinal slot 78 through which passes a screw 79, set in the block 62, to guide the plunger in its movement, the plunger being urged outwardly by a strong encircling helical spring 76, (see Figure 5) abutting the head 77 and lug 63, respectively.

The outer end of the head 77 is bevelled on its opposite side edges and contains a recess 81 in which is rotatably mounted a roll 82, the same being forced outwardly by the spring 76 to engage the recesses 65 in the plunger 100 ring 64, the effect being to resiliently retain the arms 24 in any of their four positions.

The locking ring 66 has four uniformly curved inner cam surfaces 67, blending into straight portions reaching to the bottoms of recesses 69 having abrupt stop shoulders 68.

A locking bolt 85 is slidably mounted in a groove 86, in the upper portion of the block 61, and held therein by cover strips 87. The bolt has at its rear a post 88, carrying a transverse pin 89, its extending ends engaging a pair of springs 90 adapted to draw the bolt outwardly so that its end is held in contact with the cam 67, and enters the recesses 69 to abut the stops 68, one of the bolt end corners 125 being square for that purpose while the opposite corner of the bolt is rounded to ride easily on the inclined surfaces of the recesses, opposite the stops when the rings are turning.

The bolt 85 is provided with an opening 91 129

directly in front of the post 88, and into which extends the curved end of lock lever 113, described in detail later.

Retrograde movement of the turnstile is prevented by a pawl 92, pivoted at 93 on a portion of the block 61, the pawl being pressed outwardly, by a spring actuated plunger 94 set in the lug 57, to engage the teeth 71 of the ratchet ring 70, and it is to be noted that the pawl is disposed in one of the spaces 72 of the ring when the turnstile arms are in their normal position, the purpose being to allow a moderate movement of the arms for operating the coin mechanism.

Returning to the coins, which have previously been traced to rest upon the upper edge of the baffle 50, as may best be seen in Figures 4 and 6, these coins being guided at their sides between the adjacent walls 95-96 of the chute 42, the walls each having apertures 97-98, of lesser diameter than the coins, one side of each coin being clearly visible from the outside of the mechanism through an enlarging lens 99, set in the housing 27, and it is to be noted that one side 51' of the baffle is higher than the other to receive the cent and hold it so that its center is level with the center of the nickel on the other, low side, when the coins are between the openings 97-98.

The bottoms of the coin chute plates 95-96 are spaced slightly above the edge of the baffle 50, which is pivoted at its lower side edges on pintles 100, carried in brackets 101 on the under side of the base plate 60, fixed on the lugs of the stationary frame 56, this plate also supporting footings 102 of the coin chute.

The coin chute plates 95-96 and the central partition 43 have a central recess 103, extending upwardly from their lower edges, and a corresponding, registering recess 104 is formed in the baffle 50 (see Figures 4 and 6).

A bracket 105 is secured to the chute plate 96, the bracket having rear reaching arms between which is pivoted, at 106, a lever 107, having a forked lower end engaging a pin 108, set in the baffle to cross the recess 104, in which the lever operates in swinging the baffle upon its pintles.

A projecting arm 109 on the lever 107 above its pivot has fixed in it a transversely disposed wire 110, terminating in curved right angularly bent ends 111, raised to enter notches in the tops of the apertures 97-98, when the lever is moved to let the turnstile operate, these bent ends 111 serving to return all coins entered during the operation.

Connected to the upper end of the lever 107 is one of the forked ends of a link 112, its opposite end pivotally engaging the upper end of a lock lever 113, the lower, semi-circular end of which is loosely engaged in the slot 91 of the bolt 85, as best seen in Figure 3.

The fixed base plate 60 is provided with an

opening 114, in its front portion, at the rear edge of which is a downwardly extending lug 115, and in the rear portion of the plate is another opening 116 having at its rear edge a pair of spaced downreaching lugs between which is guided a slide plate cam 118 having a convergingly beveled outer end adapted to engage the inreaching beveled cams 73 fixed in the upper edge of the ratchet ring 70.

The base plate 60 has on its upper surface longitudinal guides 119 at its side edges, the same being higher, as at 119', midway of the plate than those portions which extend from the curved front end thereof, and slidably mounted between these guides is a slide plate 120, having an opening 121, at each side of which are a pair of spaced downreaching lugs 122, making contact at their front edges with the inner end of the slide plate cam 118, the same being provided with a lug 118', these several lugs terminating in the same plane.

The slide lugs 122 are drilled transversely to receive a pin 123 on which the lever 113 normally fulcrums, and are also drilled longitudinally for the passage of headed screws 124, by which a plate 125, bridging the rear edges of the lugs 122, is secured.

The plate 125, by reason of the screws, serves to rigidly clamp the slide plate cam 118, and slide plate 120, together as an operative unit, which is pressed outwardly, to cause engagement of the cam 118 and the cams 73, by a helically coiled compression spring 126, the ends of which abut the bridge plate 125 and base plate lug 115 respectively.

The slide plate 120 is provided on its upper surface, with a pair of spaced undercut guides 127, in which is operative a locking lever slide 128, having an elongated slot 129 receptive of a pin 130, set in the slide plate 120, to limit the relative movement of the slides.

A pair of raised lugs 131 on the locking lever slide 128 are spaced to receive the locking lever 113, between them, and carry a pin 132, engaging a slot 133 in the lever, permitting relative movement, and acting as an auxiliary fulcrum for the locking lever 128, the lever extending through an opening 134 in the slide towards its main fulcrum 123.

The guides 119' on the base plate 60 have secured to them guide strips 135 which overlie the forward side portions of the slide plate 120, and extend into grooves in the coin rack slide 136, movable therein. The guide strips have inreaching hook-like elements 135' for a purpose later apparent.

Independently slidable below the caps on the coin rack slide 136 are a pair of racks 140-141 having set in their front ends detector pins 142-143, registering with the centers of the apertures 97-98 and distanced below the opposed pins 111, the rear ends of the racks, when in their innermost position,

making contact with the hook elements 137'.

These racks engage the teeth on opposite sides of a spur gear 144 mounted to freely rotate on a stud 145 set in the coin rack 5 slide 136, and from the top of the stud is a projection 146, to which is attached one end of a tension spring 147, engaging the upper end of the lever 113, drawing the locking lever slide 128 against the stop pin 130.

10 Integral with the coin rack slide 136, and rearward of the gear, are a pair of raised lugs 148 between which is pivoted a latch 150 having a stepped end 150' and midway in its length, on its under side, an angular projection 151, the latch being pressed downwardly by a flat spring 152 and fixed to a bridge 153 connecting across the tops of the lugs 148.

15 The latch projection 151 acts in the manner of a cam on the beveled upper end of a post 154 set in the fixed base plate 60 and extending upward through a slot 155 in the slide plate 120, the post 154 also acting as a stop for coin rack slide 136.

20 The operation of the mechanism will now be explained:—Should coins inadvertently escape from the fingers of a person using the turnstile and roll off the plates 32—33—34, they are readily retrieved from 25 the circuitous channel 30 at the top of the apparatus.

25 When a cent has entered the escutcheon slot 35, and pressed to pass through the projecting device 38, it is ejected with some force 30 and caused to take an angular path, inwardly towards the center, to enter the coin chute aperture 40, follow the passage 44, being deflected slightly rearward by the beveled face of the guide 46 to come to rest on the upper edge of the raised portion 50' of the baffle.

35 Similarly a nickel, passed through the slot 36 is projected downwardly at an angle to enter the aperture 41, guided by the passage 45 over the guide 47, to come to rest on the 40 lower portion of the baffle 50, the centers of both coins being essentially on the same level.

45 The coins are held upright by the walls 95—96 of the chute and central with the wall openings 97—98, being guided at their outer edges by inreaching angular blocks 49—49' and at their inner edges by the central partition 43.

50 Obviously, if an object of greater dimensions be presented at the slots 35—36, they cannot enter; if smaller objects are entered they are not subjected to the action of the devices 38—39 and therefore drop into the wide open upper end of the casing 42, following the 55 passages 51—52, conduit 54, and come to rest in the return coin box 55.

55 The same occurs in the case of entry of objects materially heavier or lighter than proper coins, and in case of entering more than one 60 coin of a kind at one time, the excess coin or

coins will be delivered by gravity through the openings 44'—45', into the passages 51—52, and pass to the return coin box, from whence the coins may be recovered.

65 However, the coins having been properly located, pressure is applied to the arm, barring the passage, causing it to start rotation of the turnstile, held against a retrograde movement by engagement of the pawl 92 with the teeth 71 of the ratchet ring 70, fixed in the 70 swivel cylinder 27, which, by reason of its rigid connection with the arm carrying band 23 is rotated by the stile arms.

75 A further obstruction is encountered by the arm, consisting of the spring pressed roll 82 80 engaged in the depressions 65 of the plunger ring 64, which is also rigid in the cylinder 27, the angular edges of the depression requiring moderate force to overcome, depending upon the yieldability of the spring 76.

85 There still remains the locking bolt 85 to overcome, the end of this bolt being pressed outwardly, by the springs 90, into engagement with the bottom of the recess 69.

90 It is to be noted that the bolt end is of lesser width than the length of the recesses 69, and normally held midway in the recesses to present an open space between its square corner and the recess abutment 68, this condition being due to the spring actuated, plunger carried roll 82, which adjusts the position of the arms after each operation, completing any deficiency and restoring them to position should they be given a slightly excessive movement.

95 Thus it will be seen that the arms may be given an initial movement, due to the yielding of the spring 75, and limited by the distance between the lock bolt edge and abutment 68.

100 One of the four equally spaced inreaching angular faced cams 73, carried by the ring 70, fixed in the cylinder, however, is in contact with the correspondingly angled end of the slide plate cam 118, causing it to move inwardly, concurrently with the initial movement of the arms, against the pressure of the 105 spring 126.

110 Such inward movement advances the slide plate 120, carrying the lever fulcrum 123 with it, and also the slides 128 and 136, together with the racks 140—141, until the detector pins 142—143 have made contact with the coins resting on the baffle 50—50'.

115 When the coins prevent further forward movement of the racks, and the coin rack slide 136, carrying the gear 144, meshed with the racks, the slide 128 is restrained from further forward movement through the intermediary of the latch 150.

120 Thus the pivot 132 in the upper portion of the lever 113 becomes stationary, but as the pivot 123 continues to advance, the top of lever 113 tilts away from the coin chute into an angular position, causing its lower round- 125

ed end to engage the post 88 and retract the lock bolt 85.

As the lever 113 is tilted it actuates the link 112, tilting the lever 107 in the same direction, which action is transmitted to the baffle in an opposite direction, due to the toggle connections, permitting the coins to drop off its upper edge and be received in the open upper ends of coin conduits 158-158', respectively for cents and nickels, whereby they are delivered to suitable separate receptacles in the cabinet base 15 accessible through the door 16.

Coincidentally with tilting the baffle to discharge coins into the chutes 158-158', the wires 111, carried by the lever 107, are caused to enter the notches above the opening 97-98, but should coins be entered at such time as the interceptor wires 111 are in the notches, the 20 coins will roll by gravity through the side passages 44'-45', over the guides 49-49', into the return coin conduits 51-52 to be restored to the operator from the cup 55.

It is to be noted that elements 65-69-72-73 and 85 are so positioned and proportioned as to present an initial yielding movement of the stile arms, followed by a smooth and uniformly easy movement until a full quarter turn has been attained and that when 30 the limit of the action is reached a cushioned effect ensues, rather than an abrupt shock.

For the purpose of illustration let it be assumed that only a cent has been entered and no nickel, or that a washer corresponding in 35 dimensions to a nickel be delivered on the baffle 50 at the opening 97.

This condition may be visually ascertained through the enlarging lens 99 in the wall of the cylinder 27, and is mechanically indicated 40 in the following manner.

Upon the forward movement of the racks, the detector pin 143 meets no resistance, passing through space if no coin be entered or through the opening in a washer like substitute.

The other pin 142, however, contacts with the side of the cent in the opening 98, and as the slide 136 advances, causes the gear 144 to turn, thus permitting further forward movement of the slide 136 and the latch 150, the latch camming off by contact between its projection 151, with the beveled top of the fixed pin 154, thus releasing the coin rack slide 136, which is drawn back against the pin 154 by the spring 147.

The racks 140-141, are carried by the coin rack slide and make contact with the inreaching hooks 135' whereby they turn the gear 144 and attain the normal uniform position, 60 but the slide 128, not having been retarded, the lever 113 will remain substantially upright and transmit no movement to the lock bolt 85.

The link 112 transmits a reverse motion to 65 the lever 107, causing the baffle to tilt and

deposit the coins or other objects that are resting on its edge into the open end of the coin return conduit 54, to arrive in the coin return box 55.

The action of the coins from the instant they have been entered through the slots 35-36, is accelerated by the spring shooting devices 38-39, on their way to the baffle, which is positioned but a short distance from the inlet, and no delay is encountered, release of the stile arms being so rapid as to be practically instantaneous with the entry of the proper coins.

Each operation of the turnstile is indicated on a counting register 160, visible through an opening in the panel 33, the register being actuated by a crank 161 having a link 162, connecting a lever 163, pivoted at 164 on a bracket 165, raised from the stationary base ring 26.

The lever is provided at its lower end, below the pivot, with an angular arm 166, disposed in the path of the cams 73 and drawn into position to operate upon contact with them by a tension spring 167.

This device could also be adapted for use on entrances, cars or busses, where a transfer system is in operation, and where the usual fare calls for the deposit of but one coin. In this modified form three slots could be used, for instance—one for a nickel for the straight fare, another for cents to pay for a transfer, if desired, and another to receive a token which would be delivered by the machine when the cents were deposited. This delivered token would obviate the necessity for the delivery by the conductor or motor-man, or other attendant of a paper transfer slip and for this reason the modification would be of great value on cars or busses with but one attendant, and at entrances where there was no attendant.

As changes of construction could be made within the scope of the invention, it is intended that all matter sustained in the foregoing description or shown in the accompanying drawings shall be interpreted as illustrative and not in a limiting sense.

Having thus described the invention, what is claimed as new and desired to secure by Letters Patent, is:—

1. A coin controlled turnstile comprising a support, a cylinder revoluble thereon, arms on said cylinder, a ring fixed in the cylinder having internal grooves corresponding to the arms, a lock bolt spring pressed to engage in the grooves to prevent turning of the cylinder, and means operable upon the deposit of a plurality of coins to retract said bolt.

2. In a coin controlled turnstile, a support, a cylinder carrying stile arms revoluble on said support, a rigid frame extending into the cylinder from the support, a cover carried by said stand, said cover having spaced entrances for a plurality of coins of unlike de-

nominations, chutes into which each coin is projected, a pivoted baffle on which the edges of the coins come to rest, a coin returning conduit on one side of said baffle, coin retaining conduits on the opposite side, means to automatically lock said cylinder, and means controlled by the coins on said baffle to permit operation on said stile arms.

3. In a coin controlled turnstile, a support, a cylinder carrying stile arms revoluble on said support, a rigid frame extending into the cylinder from the support, a spring actuated lock bolt on said frame engaging said cylinder, an upright baffle pivoted to said frame, said baffle being receptive of a plurality of deposited coins simultaneously, a slide on said frame, means in said cylinder to actuate said slide upon the initial movement of said arms, a lever pivoted in said slide, a second lever operatively engaged with said baffle, a link connecting said levers, means on said slide for mechanically actuating the levers whereby the suitability of the coins is determined, and means combined therewith for retaining proper coins, rejecting improper coins and for retracting said bolt

4. In a coin controlled turnstile, a support, a cylinder carrying stile arms revoluble on said support, a rigid frame extending into the cylinder from the support, a bolt on said frame to lock the cylinder, a lower main slide on said frame, a lever pivoted therein and engaging said bolt, a forward slide and a rear slide movable on the main slide, a tiltable baffle to receive entered coins, a lever having toggle connections with the baffle, a link between said levers, coin detector elements independently movable on the forward slide, a spring pressed latch on the forward slide normally spacing the rear slide, a cam on the frame to raise said latch upon an abnormal forward movement of the forward slide, such movement occurring upon failure of one or both of the detector elements to strike a coin, and means to advance the main slide upon the initial movement of said arms.

5. In a coin controlled turnstile, a support, a hollow cylinder rotatable thereon, stile arms carried by said cylinder, a frame on said support extending into the cylinder, a coin receiving baffle tiltable on said support, coin conduits at the sides of said baffle for proper and improper coins respectively, a slide on said support, means on said slide to verify the suitability of each coin, means for tilting the baffle in accordance therewith, a spring pressed bolt locking the cylinder with said frame, and means permitting the retraction of said bolt upon the reception of proper coins, said means being inoperative by improper coins or no coins.

6. In a coin controlled turnstile, a support, a hollow cylinder rotatable thereon, stile arms carried by said cylinder, a frame on said support extending into the cylinder, a coin re-

ceiving baffle tiltable on said support, a bolt spring pressed to lock said cylinder to the frame, a main slide, a forward and a rear slide on the main slide, a gear pivoted on the forward slide, slideable racks engaging said gear on its opposite sides, detector pins in the forward ends of said racks to contact with coins on said baffle, means to return said racks to their initial position after operation, a latch pivoted in the forward slide to normally abut the rear slide, means for camming off said latch upon excessive forward movement of the forward slide, a lever pivoted in the main slide to retract said bolt, means to tilt said lever upon the advance of the rear slide, and means to transmit movement of said lever to said baffle.

In testimony whereof I have hereunto affixed my signature.

GEORGE E. GROVER.
